UNITED STATES PATENT OFFICE.

REZIN HOSFORD, OF LEBANON, INDIANA.

GRAVEL OR SAND DREDGE.

SPECIFICATION forming part of Letters Patent No. 727,632, dated May 12, 1903.

Application filed March 9, 1903. Serial No. 146,968. (No model.)

To all whom it may concern:

Be it known that I, REZIN HOSFORD, a citizen of the United States, residing at Lebanon, in the county of Boone and State of Indiana, have invented certain new and useful Improvements in Gravel or Sand Dredges, of which the following is a specification.

As is well known, the most desirable gravel for streetwork, cement walks, and such like uses is obtained from the bottoms of streams or rivers.

It is the object of my present invention to provide a means by which gravel and sand can be easily, rapidly, and inexpensively taken from gravel-beds located in or under water.

An apparatus illustrating said invention will be first fully described, and the novel features thereof then pointed out in the claims.

Referring to the accompanying drawings, which are made a part hereof and on which similar reference characters indicate similar parts, Figure 1 is a side elevation of such an apparatus as the same appears in use in taking gravel from a gravel-bed at the bottom of a stream or body of water; Fig. 2, a top or plan view of a fragment of the conveyer and dredge on an enlarged scale; Fig. 3, a central sectional view of the same, and Fig. 4 a detail sectional view through the wheel over which the dredge and conveyer runs at the end of the apparatus opposite that to which the power is applied.

In constructing this apparatus I provide two suitable frames 21 and 20 upon opposite banks of the pit from which the gravel or sand is to be taken and mount upon one a driving-wheel 22, by which the dredge and conveyer is to be propelled, and upon the other an idler-wheel 23 of peculiar form over which said dredge and conveyer runs. Upon the same shaft as the wheel 22 I mount another wheel or pulley 24, which is driven by means of a belt, rope, or chain from some suitable source of power. (Not shown.)

The dredge and conveyer proper, as best shown in Figs. 2 and 3, consists of a chain composed of U-shaped links 25 and 26, pivotally connected together by suitable rivets 27. The links 25 are chain-links simply. The links 26 are substantially triangular in form

and constitute also the buckets for the dredge and conveyer, by means of which the sand or gravel is taken from the bottom of the pit or gravel-bed and drawn up onto the bank and there deposited to be hauled away. As indicated in Fig. 1, the power is applied at that end of the structure which is on the bank opposite from that where the material is to be deposited, and the direction of motion is such that the pull is upon the upper or idle strand of the dredge and conveyer, so that the lower or operative portion thereof contains the "slack," and thus bags down and drags on the bottom of the bed or pit being excavated, and the links or buckets 26 engage with the material and draw it out in the manner indicated by the drawings.

It sometimes happens in the use of such apparatus as this that the dredge will cut a comparatively deep channel, and the banks in such cases are likely to cave in, thus stopping the operation of the dredge. In such cases it is only necessary to reverse the motion of the engine or driving mechanism, when the dredge-chain will be easily drawn to the surface as the open links permit the gravel and sand (as the chain is tightened up) to slip down through without much resistance, the shape being especially adapted to this result, as will be readily seen.

The wheel 23, over which the dredge and conveyer runs, is of a peculiar form. Centrally around its periphery is an annular rib or flange 31, which serves to support the links at the pivot-points, while the shoulders on each side of said rib support them at the centers, thus furnishing a good support for the dredge or conveyer in its work. Guard-arms 32 are secured to the sides of this wheel and prevent the dredge and conveyer chain from accidental displacement.

Having thus fully described my said invention, what I claim as new, and desire to secure by Letters Patent, is—

1. The combination of two suitable frames, a driving-wheel mounted on one, an idle wheel mounted on the other, and a dredge and conveyer structure composed of the open links 25 and 26 mounted thereon, said links 26 being wider than the links 25 at one end and having inclined cross members whereby they are enabled to act as buckets in the

dredging and conveying operation, substantially as set forth.

2. The combination, of two frames, a driving-wheel mounted on one, an idle wheel mounted on the other, and a dredge or conveyer of a length considerably greater than double the distance between said two wheels whereby the lower or operative side is given a large amount of "slack" and thus enabled to descend into and drag upon the bottom of the pit being dredged, substantially as shown and described.

3. The combination of two frames, a driving-wheel mounted on one of said frames, an

idle wheel mounted on the other of said frames, and an endless gravel dredge and conveyer running around said wheels said idle wheel having a central annular rib and guard members, substantially as shown and described.

In witness whereof I have hereunto set my hand and seal, at Indianapolis, Indiana, this 6th day of March, A. D. 1903.

REZIN HOSFORD. [L. s.]
